HARD FIBER CARDING MACHINE

Barend Gysbertus Hendrikus van der Jagt, Mayaguez, P. R., now by change of name Barend Gysbertus Henry Vanderjagt

Application April 12, 1945, Serial No. 587,962

3 Claims. (Cl. 19—99)

1

My invention relates to an improvement in carding machines for so-called hard fibers, such as jute, coconut fibres, sisal, and palmetto root fibers, and more particularly to novel means for reducing the loss of fibers in the operation of such carding machines.

In hard fiber carding machines, it has, heretofore, been the custom to enclose the lower part of the carding cylinder and such stripper and worker rollers as may be arranged at the periphery of the lower half of the carding cylinder with a substantially solid sheet metal or wood casing extending substantially along the contours of the lower half of the carding mechanism for the purpose of preventing the fibers carried around by the carding pins from being thrown out and becoming lost. In order to reduce the friction of the fibers against this casing and to permit the escape of dust and of very short fibers, the casing was provided with two to three transverse openings and rollers were provided in these openings with their peripheries spaced a short distance from the edges of the openings so that 4 to 6 narrow transverse slots of about $\frac{1}{2}$ " width were formed in the casing. In spite of the small number and narrow width of these slots, it was found that not only the dust and the useless very short fibers were discharged through the slots, but also a considerable proportion of serviceable longer fibers. In some cases the loss of valuable fibers ran as high as 15%.

It is the principal object of the present invention to reduce this loss and to provide means whereby almost none of the valuable fibers are thrown out during their travel along the lower peripheries of the carding elements.

Another object of the invention is to provide means whereby during the travel of the fibers along the lower part of the periphery of the carding elements, at the election of the operator, either dust alone or dust and short fibers up to a certain length are discharged.

I have discovered that the high percentage of loss of serviceable fibers in the conventional hard fiber carding machines is not due to the fact that the dust escape slots are too wide or too numerous, but this loss is caused by the high velocity of the air currents passing through the slots. The main carding cylinder has a diameter of between about 4 and 5 feet and revolves at 200 or more revolutions per minute. This cylinder acts as a powerful fan which draws air into and compresses it in the casing. Due to the small number and the narrow width of the escape slots, the compressed air passes the slots in the form of air

2

currents of high velocity, and these high velocity air currents entrain even comparatively long fibers and guide them outwardly through the escape slots.

5 I have found that such high velocity air currents and the ensuing high loss of valuable fibers can be almost completely avoided if the lower part of the carding elements is enclosed not with a solid casing having only a few, narrow slots, 10 but with a screen provided with a great number of comparatively narrow uniformly spaced slots parallel to the axis of the carding cylinder, the total area of said slots being sufficient to prevent the air currents produced by the rapidly rotating cylinder from reaching at any of the slots a velocity whereby serviceable fibers are blown out through the slots.

15 The width of the slots may vary between about $\frac{1}{8}$ " and about 1" depending upon whether it is 20 desired to discharge only the dust or also the short fibers up to a certain length.

20 The width of the solid screen portions between the slots may be, for instance, about $\frac{1}{2}$ ". The number of slots per unit of peripheral length of 25 the screen may vary in rather wide limits depending upon the width of the slots and of the solid intermediate portions, but I have found that best results are obtained with from about 8 to about 20 slots per foot of peripheral length of 30 the screen.

Although in my arrangement, the number of escape slots is between 10 and 20 times that of the escape slots in the previously known constructions and the total escape area from about 35 8 to 30 times greater than in conventional hard fiber carding machines, the improved distribution of the air flow and the small velocity of the air currents passing the individual slots leads to an almost miraculous reduction in the loss of 40 valuable fibers. In hard fiber carding machines provided with my screen, the loss of valuable fibers has been found to be of the order of 1% or less.

45 Although no rollers are provided in my screen, it was found that, due to the more uniform distribution of the air currents, excessive accumulations of fibers and undesirable frictional stresses on the screen are fully avoided.

I have also found that by varying the distance 50 between my screen and the tips of the carding pins between about $\frac{1}{8}$ " and $\frac{5}{8}$ ", I can change from an operation of the machine in which only dust is discarded through the slots progressively to operations in which short fibers up to a 55 desired length are thrown out with the dust.

Several embodiments of my invention are set forth in detail in the following description and illustratively exemplified in the accompanying drawing in which:

Fig. 1 is a diagrammatic sectional side view of an up striker carding machine provided with a screen according to my invention, the carding pins and screen elements being shown on a disproportionately larger scale for the sake of clarity.

Fig. 2 is a sectional side view on a larger scale of a part of the machine illustrated in Fig. 1, showing a fragment of the carding cylinder and of the screen with the carding pins and screen elements in their proper proportions.

Fig. 3 is a diagrammatic sectional view similar to that of Fig. 1 of a down striker carding machine.

Figs. 4 to 6 illustrate diagrammatically an up striker carding machine with a screen composed of adjustable arcuate sections, the feed roller stripper, worker and doffer rollers being omitted from these figures for the sake of simplicity and the carding pin and screen elements being shown on a disproportionately larger scale. Specifically

Fig. 4 is an end view of the machine, and

Figs. 5 and 6 are sectional views taken on lines V—V and VI—VI, respectively.

Referring now to the drawings, and first to Figs. 1 and 2, 11 denotes the main carding cylinder of an up striker carding machine for hard fibers. 12 is a feeder roller, 13 and 14 are workers and strippers, two pairs of which are shown in Fig. 1. 15 is a doffer roller which removes the carded fibers from the main carding cylinder at the delivery side. Each of the various carding elements, such as the main carding cylinder, the feeder, the strippers and workers and the doffer, carries on its periphery outwardly projecting carding pins. In the embodiment according to Fig. 2, these pins project a distance of about $\frac{1}{8}$ " and are uniformly spaced about $\frac{1}{2}$ ", as usual in carding machines for hard fibers. The main carding cylinder has a diameter of about 4 feet and a transverse width of about 6 feet and its lower part is enclosed by a screen 17 which extends downwardly from a horizontal plane disposed a short distance below the cylinder axis along the periphery of the carding cylinder at a small distance, shown in Fig. 2 to be about $\frac{1}{4}$ ", from the tips of the carding pins 16. The screen 17 consists of a number of uniformly spaced round iron bars 18 extending parallel to the axis of the carding cylinder. As shown in Fig. 2, the bars 18 have a diameter of $\frac{1}{2}$ " and are arranged with their centers about $\frac{1}{16}$ " apart so as to define between them elongated slots 19 of $\frac{1}{16}$ " width running parallel to the cylinder axis. In this case about 100 bars may be placed underneath the carding cylinder 11, forming 99 slots with a total open area of $99 \times 72 \times \frac{1}{16} = 1335$ sq. inches, whereas the total escape area in the usual card casing is between $4 \times 72 \times \frac{1}{2} = 144$ and $6 \times 72 \times \frac{1}{2} = 180$ sq. inches.

The arrangement shown in Fig. 3 is substantially similar to that illustrated in Figs. 1 and 2 with the exception that in the down striker carding machine according to Fig. 3, a stripper 13a and a worker 14a are disposed below the main carding cylinder 11, instead of above said cylinder, and the positions of the feeder roller 12 and of the doffer 15 are reversed. The screen 17a includes an epicyclic portion 17b which encloses the stripper 13a and the worker 14a.

The adjustable screen 20 shown in Figs. 4 to 6

75

comprises two lateral arcuate flat iron holders 21 each consisting of three arcuate sections 21a, 21b and 21c. The holders 21 are provided with holes in which the ends of the bars 18 are mounted. Each arcuate section has radially projecting therefrom three lugs 22, the lugs of each section being provided with elongated slots 23 parallel to the radius of the cylinder 11 which passes through the center of the section. Threaded bolts are mounted in and project at right angles from the side plates 24 of the machine frame through the elongated slots 23, and wing nuts 25 on said bolts permit of clamping the holder sections 21a, 21b and 21c in position.

Two intermediate arcuate holders 26, each comprising three arcuate sections 26a, 26b and 26c, substantially similar to the sections 21a, 21b and 21c and provided with holes traversed by the bars 18, are disposed between the lateral holders 21. An I beam 27, which forms part of the machine frame, is disposed below the carding cylinder 11 parallel to the cylinder axis. At the location of each intermediate holder 26, a flat iron bar 28 provided with longitudinal slots 29 is placed on edge on the beam 27 and secured to the latter, e. g. by welding, in a position with its major axis running at right angles to that of the beam. Two uprights 30 are mounted near the opposite ends of each bar 28, by means of threaded bolts 31 extending through the horizontal slots 29 and through vertical slots 32 in the lower ends of the uprights 30 and of wing nuts 33 on the bolts 31. Integral with the upper end of each upright 30 is an arcuate yoke portion 34. The adjacent ends of associated yoke portions 34 fit slidably into recesses in the opposite ends of the associated central holder section 26b, while the outer end of each yoke portion 34 engages a recess in one of the outer holder sections 26a or 26c and serves as support for said section.

In order to increase the distance between the screen 20 and the tips of the carding pins 16, the wing nuts 33 are loosened and the uprights 30 are shifted downwardly relative to the bolts 31 and outwardly with the bolts 31 until their yoke portions 34 have assumed the desired positions, away from the holders 26 which are retained in their original positions by the bars 18 and holders 21. Then, the nuts 33 are tightened again, and, after the wing nuts 25 have been loosened, the holder sections 21a, 21b and 21c are shifted downwardly and outwardly, each along the radius of the card cylinder 11 passing through its center, until the holder sections 26a, 26b and 26c, which follow the movement of the sections 21a, 21b and 21c are seated again on the yoke portions 34. Finally, the nuts 25 are tightened again. If the distance between the screen 20 and the tips of the carding pins 16 is to be reduced, the adjustment is effected in reverse order.

I claim:

1. In an up striker carding machine for hard fibers, the combination with a machine frame and a main carding cylinder of between 4 and 5 feet diameter rotatably supported in said frame and carrying on its periphery outwardly projecting carding pins uniformly spaced a distance of about $\frac{1}{2}$ ", of a screen enclosing the lower part of said carding cylinder downwardly from a horizontal plane disposed a short distance below the cylinder axis, said screen comprising a plurality of transversely spaced curved holders extending along the periphery of said lower part of said carding cylinder, each of said holders including three arcuate sections, a plurality of transverse

bars supported by said holders in substantially parallel relationship to the cylinder axis and uniformly spaced to define between them a substantial number of evenly distributed comparatively narrow slots with a total open area sufficient to prevent the air currents produced by the rapidly rotating carding cylinder from reaching at any of said slots a velocity whereby serviceable fibers are blown out through said slots, and means supporting each said arcuate section for adjustment along a radius of said carding cylinder passing approximately through the center of said section to permit of varying the distance of said screen from the tips of said carding pins.

2. A combination, as claimed in claim 1, in which said supporting means for the arcuate sections of at least one of said holders includes radially projecting lugs on each section of said holder, the lugs on each section being provided with elongated slots parallel to the radius of said drawing cylinder passing through the center of the section and bolts projecting from the machine frame parallel to the cylinder axis through said slots.

3. A combination, as claimed in claim 1, in which said supporting means for the arcuate sections of at least one of said holders includes two uprights disposed in spaced relationship in a

common plane at right angles to the axis of the carding cylinder, said uprights being horizontally and vertically adjustable in said plane, and an arcuate yoke at the top of each upright to support one outer arcuate section and one end of the inner arcuate section of said holder.

5 BAREND GYSBERTUS HENDRIKUS
VAN DER JAGT.
